UNITED STATES PATENT OFFICE.

LEO F. NOIROT AND OTTO G. NOIROT, OF PEORIA, ILLINOIS.

DESIGN FOR A TOY ROCKER.

55,429.

Specification for Design.

Patented June 8, 1920.

Application filed December 19, 1919. Serial No. 346,187. Term of patent 7 years.

To all whom it may concern:

Be it known that we, LEO F. NOIROT and OTTO G. NOIROT, citizens of the United States, residing at Peoria, in the county of Peoria and State of Illinois, have invented a certain new, original, and ornamental Design for a Toy Rocker; and we do hereby declare that the following is a full, clear, and exact description of the invention, which will enable others skilled in the art to which it appertains to make and use the same.

Figure 1 of the drawing shows the toy rocker in perspective.

Fig. 2 is a side elevation of the same, and Fig. 3 is an end elevation.

We claim:

The ornamental design for a toy rocker as shown.

In testimony whereof we affix our signatures in presence of two witnesses.

LEO F. NOIROT.
OTTO G. NOIROT.

Witnesses:

V. V. CARLEY,
L. M. THURLOW.
